(57) **CLAIM**

The ornamental design for base for a safety child seat, as shown and described.

DESCRIPTION

1. Base for a safety child seat

1.1 is a rear view.

1.2 is a bottom view.

1.3 is a front view.

1.4 is a right side view.

1.5 is a perspective view.

1.6 is a left side view.

1.7 is a top view.

In the drawings, the broken lines represent portions of the base for a safety child seat that form no part of the claimed design.

Base for a child seat to be mounted on the rear seat of a car.
